PROTECTING DEVICE FOR BASEBALL UMPIRES

Claude R. Tobin, St. Louis, Mo.

Application April 30, 1934, Serial No. 723,055

7 Claims. (Cl. 2-2)

This invention relates to a novel athletic protecting device that is intended to be worn by a baseball umpire during the performance of his duties.

5 The main object of my invention is to provide an athletic protecting device that will not restrict or interfere with the free movements of the user's body and which is of such design and construction that it will protect the user's chest, abdomen 10 and shoulders from injury produced by a thrown or batted ball, or resulting from collision with a ball player.

Another object is to provide a protecting device of the kind above described, that is light in 15 weight, inexpensive to construct and of such design that it can be easily adjusted to adapt it to users of different sizes.

Figure 1 of the drawing is a front elevational view of my improved athletic protecting device. 20 Figure 2 is a side elevational view of said device.

Figure 3 is a rear elevational view.

Figure 4 is a sectional view, taken on the line 4-4 of Figure 1, looking in the direction indicated by the arrows; and

25 Figure 5 is a fragmentary front elevational view, illustrating the adjustability of the cover plates that are arranged over the gaps or joints between the shoulder cap guards and the collar bone protectors.

30 In the accompanying drawing which illustrates the preferred form of my invention, A designates a chest and abdomen shield, which is of such shape and dimensions that it will completely cover the user's chest and abdomen, said shield consisting of a single rigid or inflexible member that is made substantially concavo-convex shaped in transverse cross section, so that when it is mounted in operative position on the user's body, it will conform approximately to the shape 35 or outline of the user's body and extend unbrokenly or continuously across the user's chest and downwardly over the user's abdomen. The lower portion of the shield A is provided with rounded corners 1, and the upper portion of said shield which is of less width than the lower portion, is provided with inclined or curved side edges 2 that merge into the straight, vertically-disposed side edges 3 of the lower portion of the 40 shield. Said shield may be formed of various kinds of materials, but I prefer to construct it from a sheet of hard fibre that is molded or pressed into shape and which is of sufficient thickness to successfully withstand the violent 45 shocks or blows to which it is subjected when in

use. If desired, the shield A may be provided with ventilating openings 4.

At the upper end of the shield A are two integral curved portions A' that extend upwardly and rearwardly across the user's shoulders and terminate at the rear side of same, so as to afford adequate protection to the user's collar bones, the inner opposed edges 5 of said collar bone protectors A' being curved and merging into a concaved neck opening 6 at the upper end of the shield A. 10 In addition to the collar bone protectors A', the device comprises shoulder cap guards B that are hinged or pivotally connected to the collar bone protectors A' in such a way as to produce a substantially universal connection between said parts 15 which permits the shoulder cap guards to partake of the movement of the user's shoulder caps, and thus not restrict or interfere with the movement of the user's arms. The particular method of combining the shoulder cap guards B with the 20 collar bone protectors A' is immaterial, so long as said parts are connected together in such a way that the shoulder cap guards are capable of rocking vertically and also twisting and assuming an angular position with relation to the collar bone 25 protectors. I prefer, however, to provide each shoulder cap guard B with an inwardly-projecting hinge piece 7 made of leather or other suitable flexible material that is joined to its co-acting collar bone protector A' by means of a thong or 30 lacing 8 that is laced through holes in the hinge piece and holes 8a in the collar bone protector, as shown in Figures 3 and 4. Preferably, each collar bone protector A' is provided with two or more sets of holes 8a located different distances from 35 the outer edge of the protector, so as to permit the shoulder cap guards to be adjusted inwardly and outwardly, and thus adapt the device to users whose shoulders are of different width. The joints or gaps between the shoulder cap guards 40 and the collar bone protectors are protected by cover plates C mounted on the collar bone protectors A' and proportioned so that they will lap over the inner edge portions of the shoulder cap guards, as shown in Figure 1. The cover plates 45 C may be made from pieces of molded or pressed hard fibre, and they are preferably secured to the collar bone protectors by the thongs or lacings 8 used to hinge or pivotally connect the shoulder cap guards to the collar bone protectors. The 50 cover plates C are also capable of being adjusted inwardly and outwardly relatively to the collar bone protectors, and are herein illustrated as being provided with a plurality of sets of lacing holes 9 located different distances from the inner 55

edges of said plates, thereby enabling the cover plates C to be adjusted so that they will project laterally a considerable distance from the side edges of the collar bone protectors, as shown in Figure 5, when the device is to be used by a person provided with broad shoulders, or adjusted in a position where they project only a slight distance laterally from the collar bone protectors, as shown in Figure 1, when the device is to be worn by a person having narrow shoulders.

The shoulder cap guards B are preferably formed from molded or pressed hard fibre, and are of substantially concavo-convex-shape or form. Each of said guards is provided at its peripheral edge with a pad 10 constructed of felt or other suitable material, and in order to prevent the guards B from bearing directly on the user's shoulder caps, and thus perhaps causing injury to same, in the event of a violent shock or blow, each of the guards B is provided with a shock absorber, formed preferably from two right-angularly-disposed pieces of webbing 11 and 12 stretched taut on the underside of the guard. As shown in Figure 3, the shock absorbing element 11 of each shoulder cap guard is disposed transversely of the user's shoulder and is connected at its opposite ends to the front and rear edges of the guard. The other shock absorbing element 12 is attached at its inner end to the shock absorbing element 11 and attached at its outer end to the terminal edge or outer end of the guard, thereby co-operating with said element 11 to form a shock absorber that holds the guard in spaced relationship with the shoulder cap which the guard protects.

It is immaterial what type or kind of means is used to hold the shield A in operative position on the user's body. I prefer, however, to employ a holding or retaining means that comprises a belt piece D which extends transversely across the user's back in the zone of the waist line, and a substantially V-shaped back stay or brace E attached at its upper end to the terminals of the collar bone protectors A' and connected at its lower end to the belt piece D in such a way that it can shift relatively to said belt piece sufficiently to adapt itself to the movements of the user's body. In the form of my invention herein illustrated the back stay or brace just referred to is composed of two strips or pieces of webbing whose lower ends are joined together by a connecting member E' formed preferably from a piece of leather to which the lower ends of said strips or pieces of webbing are secured by stitches or in any other suitable way, as shown in Figure 3. The upper ends of the said straps or pieces of webbing are inserted through horizontally-disposed slits 13 formed in the collar bone protectors A' and are permanently connected to same by rivets 14. The connecting piece E' at the lower end of the back stay is provided with parallel, vertically-disposed slits 15 through which the belt piece D passes, thereby enabling said connecting piece to shift longitudinally of the belt piece. The belt piece D is preferably formed from two strips or pieces of webbing that are adapted to be detachably connected together by a buckle 16, one of said strips or pieces of webbing being permanently attached to one edge of the shield A and the other strip or piece of webbing being adjustably connected to the other edge of the shield A.

In order to prevent the lower end portion of the shield A from bearing directly against the user's abdomen and thus perhaps causing injury

to same, in the event said shield is subjected to a violent shock or blow, a shock absorbing device F is positioned on the inner side of the shield A adjacent the lower end of same. Said shock absorbing device F is herein illustrated as being formed from a relatively wide piece of non-stretchable webbing stretched taut across the inner side of the shield A, so as to hold the lower portion of the shield out of direct contact with the user's abdomen. The piece of webbing that constitutes the shock absorbing device F is provided at its ends with reinforcements 17 formed preferably from pieces of leather, and said piece of webbing is adjustably connected to the shield A in such a way that the length of same can be varied to take up the slack in same, thereby enabling the shock absorbing device F to be maintained in a taut or tightly stretched condition. In the form of my invention herein illustrated the shock absorbing device F is connected to the shield A by means of thongs or lacings 18 inserted through holes in said shield and co-acting holes 19 in the reinforced end portions of the shock absorbing device F, each of said reinforced end portions having a plurality of rows of holes 19, as shown in Figure 3, so as to enable the length of the device F to be changed for the purpose previously described.

Having thus described my invention, what I claim as new and desire to secure by Letters Patent is:

1. An athletic protecting device, comprising a substantially rigid and inflexible shield formed by a single member that extends unbrokenly across the user's chest and downwardly over the user's abdomen, substantially rigid collar bone protectors at the upper end of said shield that extend over the user's collar bones and terminate at the rear side of same, shoulder cap guards hinged or pivotally connected to said collar bone protectors, and means for holding said shield in operative position on the user's body.

2. An athletic protecting device of the kind described in claim 1, in which the shoulder cap guards are adjustably connected to the collar bone protectors, and cover plates are arranged over the joints between the shoulder cap guards and the collar bone protectors.

3. An athletic protecting device, comprising a substantially rigid or inflexible shield of curved shape in transverse cross section, formed from a single member that extends unbrokenly across the user's chest and downwardly over the user's abdomen, integral collar bone protectors at the upper end of said shield that extend over the user's shoulders and terminate at the rear side of same, shoulder cap guards, adjustable means for hinging said guards to said collar bone protectors, and cover plates on said shield that lap over the joints between said collar bone protectors and shoulder cap guards.

4. An athletic protecting device of the kind described in claim 3, in which said shield is provided at its lower end with a transversely-disposed shock absorbing device that holds the bottom edge of said shield spaced slightly away from the user's body.

5. An athletic protecting device of the kind described in claim 3, equipped with a shock absorbing device formed by a piece of webbing stretched taut across the inner side of the shield at the extreme lower end of same, and means for enabling the tension of said webbing to be varied.

6. An athletic protecting device comprising a substantially rigid and inflexible shield that pro-

- 5 tects the user's chest, abdomen and collar bones, and means for holding said shield in operative position on the user's body comprising a belt piece that extends transversely across the user's back in the zone of the waist line, and a back brace attached at its upper end to the collar bone protecting portions of said shield, and joined at its lower end to said belt piece in such a way that it can shift relatively to said belt piece.
- 10 7. An athletic protecting device, comprising a combined chest and abdomen shield of substantially curved shape in cross section, made from

a piece of molded or pressed hard fibre, said shield being provided at its upper end with integral, curved collar bone protectors that extend over the user's shoulders and terminate at the rear side of same, a belt piece secured to the side edges of said shield, and a substantially V-shaped back brace attached at its upper ends to the terminals of said collar bone protectors and provided at its lower end with a part that is slidingly mounted on said belt piece.
